UNITED STATES PATENT OFFICE.

JOSEPH R. H. HINTON, OF BALTIMORE, MARYLAND, ASSIGNOR TO THE
CONTINENTAL CASH CAR COMPANY, OF SAME PLACE.

PARCEL-CARRIER.

SPECIFICATION forming part of Letters Patent No. 287,129, dated October 23, 1883.

Application filed September 28, 1883. (No model.)

To all whom it may concern:

Be it known that I, JOSEPH R. H. HINTON, of Baltimore, in the county of Baltimore and State of Maryland, have invented certain new and useful Improvements in Cash and Parcel Carriers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

These improvements relate to that class of inventions known as "parcel-carriers" for warehouses, having for their object to provide a carrier adapted for carrying parcels of greater size or bulk, as compared with those capable of being carried by carriers at present in use; and also having for an object to provide suitable mechanism whereby the basket or tray by which the parcel is held can be lowered to any desired position and there retained, and, when released, to be automatically drawn up to position against its supporting-frame and held thereto, however great be the weight of the parcel.

To these ends the invention consists in such details of construction and combination of parts substantially as will be hereinafter more particularly described, and pointed out in the claims.

Referring to the drawings, Figure 1 represents a sectional end elevation; Fig. 2, Sheet 2, a side elevation, showing in dotted lines the carrier drawn down, and as when constructed for holding parcels of great bulk. Figs. 3 and 4 represent views in detail of certain parts.

Reference being had to the letters of reference marked on the drawings, A represents the supporting-frame for the tray and operating mechanism, and which frame is divided longitudinally for its whole length, it being held together at each end by screws *a*, as shown. Formed with said frame are hangers *b*, carrying in their upper ends a grooved wheel for traveling a cable-way, such being of ordinary construction.

Supported and held between the heads *c* of the frame are spring-rollers B B, said roll-

ers being of the ordinary shade-roller construction, but having secured to one end thereof a toothed or ratchet wheel, *d*, which is engaged by a suitable pawl, substantially as will be hereinafter more particularly described. 55

Secured in the roller-cylinders are suitable flexible strips, *e*, which hold to one of their ends the basket or tray C. The manner of securing or attaching the strips to the cylinders is as follows: I lap the strips over at the opposite end to which the basket is held and stitch them, having first slipped in a wire, *i*. Then I place said inclosed wire within a channel, *i'*, which is formed by bending up one of the two edges of the cylinders before bringing them 65 permanently together, and then lapping the other edge of the cylinder over said channel, and soldering or otherwise securing the edges together. It will thus be seen that the strips will bear a very great strain without pulling 70 out of their fastenings.

Secured to one of the heads, on the inner side *c*, are two curved arms or pawls, *g*. These pawls are secured to the head by screws, as shown, on which they turn, they being connected at 75 about their middles by a toggle-link, *m*, and at their lower ends by a spring, *n*. To the toggle-link is fastened a cord, *o*, which is passed up over a pulley, *p*, secured on a small shaft, *r*, that has its bearing in openings made in 80 each side of the head, as shown, and in which it turns.

D represents the basket for holding the parcel to be carried. Said basket may be made of wire, wicker-work, or of any suitable material, its two ends being so formed as to approximate to a U shape, which will readily admit of an umbrella or parasol, or both, being placed lengthwise in the basket, while the space beneath can be occupied by smaller articles. In Fig. 2, Sheet 2, said basket is shown by dotted lines as being of increased size for carrying parcels of extremely large bulk. 90

The operation is as follows: The basket in its normal position is always up against the 95 frame, and is there held against any force which may be exerted to draw it down by the pawls *g*, which are normally always engaged with the ratchet-wheel *l* on the end of the spring-rollers B. When it is desired to draw 100

the basket down, by taking hold of the cord *o* and pulling it, which compresses the spring *n* and releases the pawls from engagement with the wheels, the said basket can be drawn down as far as desired. By letting go of the cord, the relaxation of the spring draws the pawls back into their engagement, and the basket is thus securely held to the position at which it may be drawn.

It is well known in the operation of the ordinary shade-roller that when the shade has been drawn down to any point and stopped by the peculiar mechanism of said roller, and a slight force or pull exerted on said curtain, it will suddenly fly up. Such would be the result in this case if a heavy article were placed in the basket after it had been drawn down; but it will be obvious that with my improved stop or check mechanism the basket cannot be drawn in either direction by the operator until said mechanism is released, and that in whatever position it may be placed it will there be firmly held.

What I claim is—

1. The combination, in a parcel-carrier, of the frame, constructed as described, the rollers having on one end a ratchet-wheel, with the pawls adapted to engage said wheels, for holding the suspended tray in any desired vertical position, substantially as set forth.

2. The combination, in a parcel-carrier, of the frame, the basket or tray, and means for suspending the same, and with vertically-adjusting mechanism, substantially as described.

3. The combination, in a parcel-carrier, of the frame, the tray, and the vertically-adjustable retaining mechanism, as set forth.

4. The combination, in a parcel-carrier, of the frame, the rollers provided with the ratchet-wheel, and the retaining mechanism, as set forth.

5. The combination, in a parcel-carrier, of

the frame, the rollers, the ratchet-wheels and pawls, and the toggle-links.

6. The combination, in a parcel-carrier, of the frame, the rollers, the ratchet or escape wheel and pawl, the spring, toggle-link, and the loose pulley and its shaft, with the operating-cord, as set forth.

7. The combination, in a parcel-carrier for store-service systems, consisting of the frame, the tray or basket, the rollers and flexible supports, the retaining mechanism, and the retaining devices, all operating together in the manner set forth.

8. The combination, in a parcel-carrier for store-service systems, of the frame, the basket adapted to approach to and recede from said frame, the intermediate raising and lowering devices, and the retaining mechanism, with the releasing mechanism, as set forth.

9. In cash and parcel carriers, the combination, with the frame and the spring-retaining mechanism, of the spring-rollers having the ratchet-wheel, the flexible supports, and the basket, said supports being lapped at one end, and holding a wire, and secured in the rollers, substantially as described.

10. In cash and parcel-carriers, the improved mode of fastening the supports for the tray to the spring-rollers, by which said tray is held, which consists in forming one edge of the rollers with a channel, and placing therein the ends of the supports holding the wire, as described; and then lapping the other edge of the rollers over said channel and soldering or otherwise connecting the same, as set forth.

In testimony that I claim the foregoing as my own I affix my signature in presence of two witnesses.

JOSEPH R. H. HINTON.
